LOW DENSITY DYNAMITE COMPOSITION

Harold A. Lewis, Woodbury, N. J., assignor to E. I.
du Pont de Nemours & Company, Wilmington,
Del., a corporation of Delaware

No Drawing. Application December 22, 1931,
Serial No. 582,648

11 Claims. (Cl. 52—11)

This invention relates to an improved dynamite composition, and more particularly to such a composition comprising an explosive ingredient as sensitizing agent and treated sunflower stalks 5 as a new carbonaceous combustible ingredient of dynamite.

Low density dynamites have become of particular importance in recent years. The advantage of these explosives is great in the blasting 10 of materials having relatively low resistance, such as coal, salt, and soft rock for example. Since they allow the distribution of strength of the explosive over considerable borehole wall surface, undue shattering of the material being blasted is thereby prevented. The prior art discloses fully these and the numerous other advantages of low density dynamite compositions of the several types.

The prior art discloses also several means which 20 have been employed in the production of low density dynamites in the past. For example, various carbonaceous combustible ingredients such as balsa wood, bagasse pith, ground cornstalks, ground popcorn, and the like, have been used, 25 and have proved to be very satisfactory.

The object of this invention is to provide low density dynamites containing an improved combustible ingredient having, in addition to its low density properties, the advantages of low absorption 30 value for liquid explosive ingredients, ready availability, and low cost.

I have discovered that the objects of this invention can be obtained by the incorporation in dynamite compositions of an improved carbonaceous material, namely treated sunflower stalks.

By the term "sunflower" I mean to designate all the species of genus *Helianthus*. The best known representative of this genus is the common sunflower, *Helianthus annuus*. Another suitable 40 variety of this genus is *Helianthus tuberosus*, commonly known as the Jerusalem artichoke, this variety being a preferred type because of the valuable inulin bearing tubers which are obtained as a by-product. By the term "treated" sunflower stalks is meant the product of any of several methods of preparing the sunflower stalks for incorporation in dynamite compositions. For example, these methods may consist simply of grinding, cutting, or otherwise disintegrating 45 the stalks into a product of the desired fineness, or the disintegrated material may be suitably screened with the object of removing a portion or all of the higher density fibrous material comprising the outside of the sunflower stalk, or the 50 disintegrated material either screened or un-

screened may be treated with water at elevated temperatures in order to lower its final density, and to remove water soluble materials. The treated material obtained by these several methods will have a density varying usually between 0.09 and 1.13. 5

My invention is applicable to all non-gelatinous types of explosive compositions, whether or not they contain a liquid explosive ingredient. The three main classes of those containing liquids are 10 commonly known as straight dynamites, ammonia or extra dynamites, and permissible dynamites. The straight dynamites are commonly produced in several strengths varying from about 20% to about 75% and are used for various kinds 15 of blasting, as priming agent for gelatinous explosives, in special work in which, among other things, high velocity and sensitiveness to detonation is essential. These compositions usually comprise a liquid explosive ingredient in percentage equal to their grade strength, combustible absorbents, and sodium nitrate. The ammonia or extra dynamites are likewise made in several strengths ordinarily equivalent to the corresponding straight dynamites, and are used for general 20 blasting operations. They usually comprise a lower percentage of liquid explosive than the grade strength, ammonium nitrate, sodium nitrate and combustible absorbents; for example, the 20% strength powder may have 10% to 15% 25 of liquid explosive and 8% to 15% of ammonium nitrate, and the 60% strength powder may have 25% to 30% of liquid explosive and 45% to 55% 30 of ammonium nitrate. The permissible dynamites are usually of high grade strength, from 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

By the term "dynamite", as understood in the art, there are included such blasting explosive compositions that contain liquid explosive ingredients, such as nitroglycerin, nitroaromatic compounds, or a sensitizing ingredient such as 50 nitrostarch.

Among the dynamite compositions containing no liquid explosive ingredient are those in which solid sensitizers are used, as for example, the 55 nitrostarch dynamites.

While my invention is capable of use in many different forms, for the purpose of illustration, I shall confine myself to one example each of the compositions which bring out its advantages.

5 In the compositions having the density heretofore manufactured as cited above, I may use:

	Per cent	Per cent	Per cent
Nitroglycerin	10	60	23
Ammonium nitrate	75		52
Sodium nitrate	5	20	14
Treated sunflower stalks	8	5	2
Other combustible	2	15	9

15 It will, of course, be apparent from the foregoing that I can vary the percentages of materials shown in these examples quite widely and can introduce other ingredients not mentioned without departing from the spirit of my invention. For example, I may use nitroglycerin or nitro-glycol or mixtures thereof, with or without partial substitution of tetranitrodiglycerin, nitrated sugars, nitrocompounds, and the like. I may also increase the proportion of sodium nitrate appreciably, or I may decrease the proportion or omit it entirely, in which case I may use sodium chloride. Likewise, I may use along with treated sunflower stalks, both high density combustibles, such as corn meal, ivory nut meal, flour, or the like, and low density carbonaceous materials, such as bagasse pith, cornstalks, or the like.

20 30 By means of this invention it is possible to produce straight and ammonia dynamites weighing less than 181 grams per $1\frac{1}{4} \times 8''$ cartridge, and in the case of dynamites of the permissible type this new ingredient makes it possible to obtain 35 weights of $1\frac{1}{4} \times 8''$ cartridges of less than 146 grams.

I claim:

1. A dynamite composition characterized by its 40 low density which comprises a liquid explosive ingredient and disintegrated sunflower stalks.
2. A dynamite composition characterized by its low density which comprises disintegrated sunflower stalks and more than 6% of liquid explosive ingredient.
3. A dynamite composition characterized by its 45 low density which comprises a liquid explosive

ingredient and at least 1% of disintegrated sunflower stalks.

4. An explosive composition of the permissible type characterized by its low density which comprises a liquid explosive ingredient, ammonium nitrate, a non-explosive salt adapted to reduce flame temperature, and disintegrated sunflower stalks.

5. An explosive composition of the permissible type which comprises a liquid explosive ingredient, ammonium nitrate, a non-explosive salt adapted to reduce flame temperature, and disintegrated sunflower stalks, said composition having a density such that a $1\frac{1}{4} \times 8''$ cartridge weighs less than 146 grams.

10 6. An explosive composition of the straight dynamite type characterized by its low density which comprises a liquid explosive ingredient, sodium nitrate, and disintegrated sunflower stalks.

15 7. An explosive composition of the straight dynamite type which comprises a liquid explosive ingredient, sodium nitrate, and disintegrated sunflower stalks, said composition having a density such that a $1\frac{1}{4} \times 8''$ cartridge weighs less than 181 grams.

20 8. An explosive composition of the ammonia type characterized by its low density which comprises a liquid explosive ingredient, ammonium nitrate, sodium nitrate and disintegrated sunflower stalks.

25 9. An explosive composition of the ammonia type which comprises a liquid explosive ingredient, ammonium nitrate, sodium nitrate, and disintegrated sunflower stalks, said composition having a density such that a $1\frac{1}{4} \times 8''$ cartridge weighs less than 181 grams.

30 10. A dynamite composition characterized by its low density which comprises a liquid explosive ingredient and 1 to 20% of disintegrated sunflower stalks.

35 11. A dynamite composition which comprises more than 6% of liquid explosive ingredient and more than 1% of disintegrated sunflower stalks, said composition having a density such that a $1\frac{1}{4} \times 8''$ cartridge weighs less than 181 grams.

HAROLD A. LEWIS.
